(57) **CLAIM**

The ornamental design for a floodlight, as shown and described.

DESCRIPTION

FIG. 1 is a front view of a floodlight showing our new design;
FIG. 2 is a rear view thereof;
FIG. 3 is a right side view thereof;
FIG. 4 is a top view thereof;
FIG. 5 is a bottom view thereof; and,
FIG. 6 is a cross-sectional view taken along line 6-6 in FIG. 1.
A left side view of the floodlight is omitted since the left side view is a mirror image of the right side view. The portions with double hatched lines shown in FIG. 6 are transparent.
